CHENILLE TEXTILE FABRIC OR SIMILAR ARTICLE

William Stark, New York, N.Y., assignor to Heritage
Weavers, Laurinburg, N.C., a partnership

Filed Apr. 7, 1958, Ser. No. 50,372

Term of patent 3½ years

(Cl. D92—1)

FIG. 1.

FIG. 2.

Figure 1 is a plan view of a chenille textile fabric or similar article showing my design.

Figure 2 is a sectional view taken along the line 2—2 of Figure 1.

A unit is enclosed within the dot and dash lines on the drawing, which unit is repeated in regular succession as indicated by the extension beyond the unit boundaries.

The characteristic features of my design consist of horizontal and vertical rows of thread pilings or tufts which are alternately, widely spaced, closely spaced and clustered forming stripes intersecting at right angles with irregular and heavier clusters of pilings or tufts at the intersections, forming square-like figures, the sides of which are formed by more closely spaced and heavier pilings or tufts than those disposed in the center of the figures.

I claim:

The ornamental design for a chenille textile fabric or similar article, substantially as shown and described.
